UNITED STATES PATENT OFFICE.

LEOPOLD KASSANDER AND HARRY L. LEVERETT, OF NEW YORK, N. Y., ASSIGNEES TO
NATHAN MANUFACTURING COMPANY, OF NEW YORK, N. Y., A CORPORATION OF
NEW YORK.

INJECTOR.

1,153,114.

Specification of Letters Patent. Patented Sept. 7, 1915.

Application filed April 21, 1914. Serial No. 833,402.

To all whom it may concern:

Be it known that we, LEOPOLD KASSANDER and HARRY L. LEVERETT, both citizens of the United States, and both residing at New York, in the county of New York and State of New York, have invented certain new and useful Improvements in Injectors, of which the following is a specification.

This invention relates to injectors designed for use with locomotives, and particularly to that form of injector in which, in addition to the main water supply inlet to the nozzles, there is an auxiliary water inlet through which water from the main water supply passage may pass directly into the overflow chamber; and which auxiliary water inlet is controlled by a gravity check valve, which in the art is generally termed an inlet valve, the auxiliary water supply, through said inlet to the overflow chamber, being drawn under certain conditions into the nozzles, through the overflow openings in the latter, resulting in an increased delivery capacity of the injector.

The gravity check valve above referred to may, and not infrequently does, get out of order and become leaky. When this happens, the prompt starting of the injector is interfered with. In order to prevent this, there is arranged at a suitable location near the gravity check valve referred to, a hand operated cut out valve, which in case the gravity check valve becomes leaky, may be used positively to close the auxiliary water inlet, thus permitting the injector to be continued in action until there is an opportunity to repair the leaky valve, although naturally the injector will have a somewhat reduced delivery capacity.

It is therefore an object of our invention to provide an injector with means of a simple character which will secure the effective closing of the auxiliary water inlet when the gravity valve above referred to becomes leaky.

Another object of our invention is to overcome certain difficulties which have been experienced in keeping the seat of the steam nozzle of the injector steam tight. In the usual construction of an injector, the steam has easy access to the seat made by this nozzle on the bridge separating the steam and water supply chambers and gradually eats away the metal on this seat, thereby after a time causing a leak which prevents

the proper priming or starting of the apparatus.

It is an object of our invention to remedy this defect and to that end we provide a form of steam nozzle which is provided with a tubular extension threaded into a tubular support and with a shoulder adapted to engage a flange on such support to form a tight joint at that place.

In the drawings, there is illustrated a preferred form of injector embodying our invention and in which—

Figure 1 is a longitudinal central vertical section of the apparatus, the operating handle and some of the parts being shown in elevation; Fig. 2 is an enlarged section of the steam nozzle and adjacent parts; Fig. 3 is an enlarged longitudinal vertical section and partial elevation of the inlet valve, and adjacent parts, the valve being shown in open position; Fig. 4 is a view similar to Fig. 3, with the valve shown in a closed position; and Fig. 5 is a horizontal transverse section on the plane of the line 5—5 in Fig. 4.

In the drawings, 10 is the casing or body of an injector, 11 the steam supply connection, 12 the water supply connection, 13 the overflow connection and 14 the connection leading to the boiler. A valve 15 provided with a stem 16 operated by a handle 17, controls the water inlet port. A steam valve 18 having a stem 19 and operated by a handle 20, controls the entrance of the steam into the nozzles. An overflow valve 21 is arranged to control the overflow opening.

22 is a stem operated by a handle 23.

24 is the steam nozzle and 25 is the lifting steam nozzle threaded into the steam nozzle at 26.

27, 28, 29 and 30 are the usual nozzles, and 31, 32, 33 and 34 the usual overflow openings between them.

35 is a back pressure valve arranged between the nozzle 30 and the boiler connection.

36 is the steam chamber, 37 is the water-supply chamber and 38 is the overflow chamber.

39 is the auxiliary water inlet valve housing containing the gravity valve 40 and which housing is formed integral with the casing 10 and provided with a bridge 41 provided with a port 42 the lower edge 43 of which forms a seat for the upper side of 110

the valve 40. The housing is provided with an inwardly extending annular flange 44 internally threaded and with a second inwardly extending annular flange 45 having 5 a shoulder 46.

50 is a valve casing of general tubular form. It is provided with an annular flange 51 adapted to abut squarely against the shoulder 46 of the housing 39. It is also 10 provided with a number of ports or openings 52 connecting with a passage 53 leading from the water supply chamber 37, the housing 39 being apertured to permit of the passage of the water. It is also provided with 15 an annular partition 54 threaded into the flange 44 and which partition is suitably recessed to be slidably engaged by webs 55 formed on the stem 56 of the valve 40. The lower surface of the valve 40 rests upon the 20 partition 54 and seats thereon.

Within the casing 50 there is arranged a valve stem on spindle 60 provided with a projecting annular flange 61 adapted to fit snugly against a shoulder 62 formed within 25 the casing and which stem is reduced at 63 to fit within the tubular portion 59 of the stem 56 of the valve 40 and is expanded at the upper end of such reduced portion to 30 form a head 64 which is adapted to contact with the lower surface of the valve 40. Parts of the projecting ribs 58 between the recesses in the annular partition 54 are 35 truncated as shown at 65 (see Fig. 5) so that the upper end or head 64 of the stem 60 can be inserted into the recess formed in the stem 56. The lower end of the spindle 60 is provided with a hexagonal nut 70 whereby it may be turned by means of a suitable wrench and the exterior part of the casing 50 is 40 threaded to receive a stuffing box nut 71 adapted to compress suitable packing material 72 which may be placed therein.

As stated above, difficulties have been experienced in keeping the seat of the steam nozzle of the injector steam tight because of the fact that in the usual construction of an injector the steam has easy access to the seat made by such nozzle on the bridge or partition which is provided to separate the 45 steam and water supply chambers, and this action of the steam gradually eats away the metal and after a time causes a leak which prevents the proper priming or starting of the apparatus. The means which we provide to overcome this condition is very simple. The steam valve 18 has at its front end a round stem 75 which is adapted to enter the rear end of the steam nozzle 24, this 50 valve being operated by the handle 20 as above described. The partition or bridge 76 which separates the steam chamber from the water chamber is formed into a tubular extension and is threaded as indicated at 77 and provided with an inwardly extending 55 annular flange 78, forming in effect an inter-

nally threaded tubular extension terminating in such flange. The rear end 80 of the steam nozzle is threaded externally to engage the internally threaded surface of this tubular extension and at its front end is 70 restricted to form an annular shoulder 81 adapted to abut squarely against and contact tightly with the flange 78. The contacting threaded portions of the parts described and the tight fit formed by the flange and shoulder referred to, serve in effect to form a steam nozzle having its external annular portion completely inclosed within and overlapped by the tubular extension of the partition or bridge between the steam chamber 80 and the water supply chamber, and the relatively large area of contact between the threaded surfaces effectually prevents the steam from leaking past the ends of the steam nozzle and cutting away the metal 85 to cause a leak as has heretofore occurred.

The operation of the device is as follows: The steam valve is opened just enough to admit steam through the small ports used for that purpose without withdrawing the 90 extension 75 from the interior of the nozzle 25. The steam then passes through the small openings and through the usual lifting steam nozzle indicated at 24, and the nozzle 27 and the overflow opening between nozzle 95 25 and nozzle 27 and lifting the overflow valve 21, passes out into the atmosphere creating a suction or vacuum in the injector and drawing the water through the connection 12. As soon as water issues out of the 100 overflow 13, the steam valve 18 is drawn back as far as it will go. This opens the interior of the steam nozzle 25 and allows the full supply of steam to enter the nozzles 27, 28 and 29 and forces the water through the delivery nozzle 30, past the back pressure valve 35 and boiler connection 14, into the boiler. At high steam pressure, vacuum is produced in the overflow chamber 38 which draws an additional supply of water into 110 the nozzles, through the passage 53, the valve housing 39 and port 42, and openings 31, 32 and 33, which additional water is forced with the supply coming from the chamber 37, into the boiler, thereby increasing 115 the capacity of the injector under usual conditions of operation. The position of the valve 40 when the additional supply of water is drawn into the overflow chamber is shown in Fig. 3, in which it will be observed 120 that the head 64 limits the upward movement of this valve in such a manner as to allow the water to pass through the housing 39 and port 42 into the overflow chamber. Should this valve 40 leak or be held off of its 125 seat by some obstruction, then the steam admitted to start the injector as above described will pass from the overflow chamber and thence back through the housing into the passage 53 and into the main water sup- 130

ply chamber 37, thereby heating the water going into the nozzles unduly and preventing the starting of the injector. In such case, the valve stem or spindle 60 is actuated 5 until the head 64 will press against the valve 40 and cause it to seat firmly against the annular edge 43 formed in the bridge 41, thereby closing the port 42 and preventing any steam from going back into the main water 10 supply chamber 37. This is the position of the valve shown in Fig. 4. This actuation of the spindle 60 and supplemental valve 64 enables the continued use of the injector, with a somewhat reduced capacity it is true, but 15 nevertheless an efficient use until there is an opportunity given to regrind or otherwise repair the gravity valve 40.

It should be noted that the annular partition 54 of the casing 50 forms in effect a 20 water inlet port surrounded by a valve seat and that the bridge 41 forms in effect another water inlet port 42 surrounded by a valve seat, and that the valve 40 moves between these two seats to close either port, its 25 movement downward being by gravity and its movement upward being caused by the operation of the spindle 60, the upward movement being limited by the contact of the head 64 with the lower restricted portion 30 of the valve stem of the valve 40.

We claim:—

1. In an injector, a housing provided with a water inlet port and a water outlet port, a 35 casing adapted to be received within the housing, a valve adapted to be moved to one of two positions within the housing, and means within the casing adapted to be moved against the valve to positively bring it to one of two such positions.

2. In an injector, an auxiliary water supply chamber comprising a housing provided with two partitions each provided with an aperture constituting an inlet and an outlet port, a valve adapted to be moved to and 45 fro with respect to such apertures, and means for guiding the valve in such movement.

3. In an injector, an auxiliary water inlet device comprising a housing provided with two partitions each provided with an aperture, a valve adapted to be moved to and fro with respect to such apertures and means 50 for guiding the valve in such movement comprising a valve stem provided with ribs and recesses formed in one partition adapted to 55 be engaged thereby.

4. In an injector, an auxiliary water inlet device comprising a housing provided with two partitions each provided with an aper-

ture, a valve adapted to be moved to and fro with respect to such apertures, in combination with means for moving the valve in one direction comprising a head inclosed by the valve and a stem secured thereto and adapted to be longitudinally moved by rotation.

5. In an injector, an auxiliary water inlet device comprising a housing provided with two partitions each provided with an aperture, a valve adapted to be moved to and fro with respect to such apertures, in combination with means for moving the valve in one direction comprising a head inclosed by the valve and a stem secured thereto and threaded into the housing and a device for turning it.

6. In an injector, an auxiliary water inlet device comprising a housing provided with two partitions each provided with an aperture, a valve adapted to be moved to and fro with respect to such apertures, in combination with means for moving the valve in one direction comprising a head inclosed by the valve and a stem secured thereto and threaded into the housing and a device for turning it including a nut having plane surfaces.

7. In an injector an auxiliary water supply chamber provided with two ports through which the water is adapted to pass and two optional means for closing the ports, one 90 automatic.

8. In an injector provided with an auxiliary water supply chamber, provided with an inlet and an outlet and a gravity valve adapted automatically to control the inlet 95 of the same, and also adapted to positively close said outlet, in combination with means for operating said valve.

9. In an injector, an auxiliary water supply, of a valve adapted to control said auxiliary supply and adapted to be moved between two valve seats.

10. In an injector, an auxiliary water supply, two ports through which the auxiliary water supply must pass in succession, in 105 combination with a valve adapted to be seated against either port automatically by gravity against one port and hand actuated against the other port.

In testimony whereof we affix our signatures in presence of two witnesses.
